DESIGN FOR A COMBINED ELECTRIC GRILL AND COOKER

Webster A. Parr, Chicago, Ill., assignor of one-half to Bernhard C. Grunig, Chicago, Ill.

Application January 30, 1936, Serial No. 60,893

Term of patent 3½ years

To all whom it may concern:

Be it known that I, Webster A. Parr, a citizen of the United States of America and a resident of Chicago, in the county of Cook and State of Illinois, have invented a new, original, and ornamental Design for a Combined Electric Grill and Cooker of which the following is a specification, reference being had to the accompanying drawing, forming a part thereof, and in which:

The figure is a perspective view of a combined electric grill and cooker embodying the new design, the side of the same opposite that seen in the drawing being like the side shown.

I claim:

The ornamental design for a combined electric grill and cooker, as shown and described.
